UNITED STATES PATENT OFFICE.

FRANK HINMAN PIERPONT AND JOSEPH EARL TIPTON, OF HORLEY, ENGLAND, AS
SIGNORS TO LANSTON MONOTYPE MACHINE COMPANY, OF PHILADELPHIA, PENN-
SYLVANIA, A CORPORATION OF VIRGINIA.

TYPOGRAPHIC MECHANISM.

Application filed June 11, 1923. Serial No. 644,737.

To all whom it may concern:

Be it known that we, FRANK HINMAN PIERPONT, and JOSEPH EARL TIPTON, citizens of the United States, residing at Salfords, Horley, Surrey, England, have invented certain new and useful Improvements in Typographic Mechanism; and we do hereby declare the following to be a full, clear, and exact description of the same, reference being had to the accompanying drawings, forming part of this specification, and to the characters of reference marked thereon.

This invention relates to the production, or to the casting and composing, of single types in justified lines, from "abnormal" matrices in a typecasting and composing machine, adapted to deal with "standard" matrices and wherein a movable die-case or matrix-carrier, containing a font, or series of matrices, is selectively moved, relatively to a mould, to position the required matrix, by die-case positioning mechanism, the positioned or selected matrix being finally adjusted or centred relatively to the mould and clamped thereon by a centering pin or device.

In such machines, the usual mechanism for positioning the "standard" die case comprises, for each direction of adjustment, a series of primary gauges, which correspond in number to the number of rows of matrices in the die case, and are individually actuated to cooperate with members of a positioning or translating mechanism to position a selected matrix over the mould. The primary gauges, or the various centering positions denoted by them, are at equal distances apart, and in the usual commercial machine the "standard" matrices are all of the same size, the centering distances between them being a constant and equal to the distance between successive gauges of a series. An example of a type-casting and composing machine to which the present invention is particularly applicable is described in United States Letters Patent to Bancroft No. 625,998, May 30, 1899.

The "standard" matrices, adapted to be used in the ordinary or commercial machine, are suitable for all sizes of type up to and including 12 point and all the characters required for a normal font can be placed on the same size of matrix and accommo-

dated in the usual die case, these "standard" 55 matrices being arranged in 15 rows in each direction, thus providing for 225 matrices. When it is necessary to increase the size of the matrix beyond the normal or "standard" size, for example, when types say of 14, 18 60 or 24 point are to be cast, then the ordinary arrangements cannot be retained as matrices of a size to take all the characters in such fonts will be such that the centering distances between the adjacent matrices will 65 not be equal to the distances between, or denoted by, the aforesaid gauges.

Machines, especially adapted for dealing with these larger or "abnormal" matrices alone, could be constructed, yet it is desirable that the ordinary commercial machine should be capable of dealing with such fonts when required, and several endeavors have been made to meet this requirement, such for example as described in the specifications 70 of U. S. Patents Nos. 1,008,364, 1,094,678, 1,079,321 and 1,300,811. These and other schemes involve structural alterations to the machine and the use of supplementary die-case positioning mechanism by which the 75 various centering positions given to the die case by the normal gauging devices or pins for "standard" matrices is varied or augmented to bring the selected "abnormal" 80 matrix to its exact position over the mould cavity to be acted upon by the clamping or centering pin.

The chief object of the present invention is the production of types in properly justified lines from "abnormal" matrices of a 90 font say of 14, 18 or 24 point, in a "standard" machine utilizing the "standard" gauging and positioning mechanism for directly positioning the die case and setting directly the normally constructed mould-dimensioning and justification devices. By this invention "standard" and "abnormal" matrices can be employed at will on the same machine without necessitating structural 95 alterations and avoiding the presence and inconvenience of additional mechanism involving time and attention in effecting a 100 change from one style to another.

The present invention consists of a method of arranging in the die-case "abnormal" matrices wherein the centering distance between adjacent matrices is not equal to that 105 between adjacent gauges of a series but the

centering position of each matrix coincides exactly with a centering position indicated by one of the gauges, also that while the matrices are not, or need not be of the same size throughout the die-case, or, are not or need not be arranged in unbroken rows running from side to side or from end to end of the die-case, each gauge can be employed either to centre a matrix or position the 10 justification devices.

In accordance with the present invention therefore, a die-case with "abnormal" matrices can be positioned directly to centre such a matrix over the mould by the gauging and positioning devices adopted for "standard" matrices so that the centering cavity or point in a matrix is brought exactly under the matrix centering pin or device of the existing machine, and the full 20 range of "standard" justification positions is available.

In accordance with this invention also the matrices can be supported or suspended in staggered or broken rows as distinguished 25 from unbroken rows in the normal machine, being supported by suspension bars or rods which pass through central openings in certain matrices and rest in transverse or lateral external grooves in other matrices. 30 This arrangement provides for an increased number of available centering positions and therefore a greater variety of unit values.

Referring to the accompanying drawings:—

Fig. 1 is an inverted plan view of a die case showing the character end of the matrices.

Fig. 2 is a similar view of the die case shown in Fig. 1 with the matrices removed, 40 their positions being indicated by broken lines.

Fig. 3 is an inverted plan view of another arrangement wherein the matrices are staggered or placed in broken or incomplete rows.

Fig. 4 is a similar view of the die case shown in Fig. 3 with the matrices removed, the matrix positions being indicated in broken rows.

Fig. 5 is a section on the line 5—5 of Fig. 3.

Fig. 6 is a section on the line 2—2 Fig. 4 and looking in the direction indicated by the arrows 6—6, and

Fig. 7 is a section on the line 2—2 Fig. 4 looking in the direction indicated by the arrow 7—7.

In carrying the invention into practice, the matrix-carrier A is formed with a larger opening a to receive the font of matrices, than in the "standard" matrix-carrier so that the opening is now of such dimensions as would accommodate 256 "standard" matrices arranged in 16 rows in either direction, as against 225 "standard" matrices

arranged in 15 rows in either direction as hitherto. The matrices employed in the present invention are conveniently of two sizes, some B, being equal in dimensions to two "standard" matrices and others, B¹, equal in dimension to four "standard" matrices.

The matrices, as hitherto, are arranged in horizontal rows according to the unit values of the characters, symbols, etc., which they

carry, and in vertical columns. In the arrangement shown in Fig. 1 the first horizontal row (reading from the top of the drawing) contains characters each say, of

6 units value; the second row, characters of 8 units; the third row, characters of 10 units; the fourth row, characters of 11 units; the fifth row, characters of 13 units; the sixth row, characters of 14 units; the seventh row, characters of 15 units; and the eighth row, characters of 16 units:

This arrangement provides for characters of eight different unit values; which, while restricted, provides for a practical font of

matrices to be cast of their proper apportionment or value. There are fifteen matrices, in each of the first four horizontal rows of the die-case.

The matrices B in these four horizontal rows are each equal in dimensions to two "standard" matrices, with the exception of one matrix B¹, at the extreme left end of each row, these matrices being equal in dimension to four "standard" matrices.

There are eight matrices B¹ in each of the four remaining horizontal rows, the matrices B¹ in these four rows being each equal in dimension to four "standard" matrices.

The die case is provided, as hitherto, with a perforated protecting plate A¹ (see Fig. 105 2) which has openings A² coinciding with centering cavities in the matrices B and B¹, and all matrices except those from which

low-quads or spaces are to be cast, are furnished with such centering cavities.

In Fig. 2 the openings A² in the plate A are shown and these openings coincide with the centering cavities b in the matrices and in Fig. 2 the matrices are indicated by

broken lines so that the position of the centering cavity in the matrix is shown.

For positioning the horizontal rows of matrices by the existing die-case positioning mechanism and gauge pins, the pin No.

1 of the series X is utilized for the first row and the centering cavities in the matrices are so located that when the gauge pin No.

1 is operated, as hitherto by a signal in the record strip, the die case will be moved to bring one of the matrices in this row with

its centering point or cavity directly under the existing matrix-centering or clamping pin of the machine, similarly the second row of matrices is positioned by the gauge pin

No. 3 of the series; the third row, by the

130

pin No. 5 of the series, and so on for the remaining rows.

131

For the purpose of centering the matrices in the die-case, the matrices are provided with

132

centering pins or points, which are located in the matrices so that when the gauge pin No.

1 is operated, the centering pin or point in the first matrix in the first row is positioned

133

gauge-pin No. 5; the fourth row by the gauge-pin No. 7; the fifth row by the gauge pin No. 9; the sixth row by the gauge-pin No. 11; the seventh row by the gauge-pin 5 No. 13; and the eighth row by the gauge-pin No. 15; all as indicated by the broken lines x (see Fig. 2). In this embodiment of this invention each alternate gauge-pin of the series for positioning the rows according to 10 the unit value of the matrices is employed.

There are fifteen vertical columns of matrices but these do not, in the present example, extend from end to end of the die case. In each vertical row, with the exception of the fifteenth there are four matrices B of the smaller dimension, and in the fifteenth row are eight matrices B^1 of the larger dimension. In the remaining portion of the die-case are seven vertical columns 20 each having four matrices B^1 of the larger dimension.

The centering cavities b in the matrices are arranged so that the gauge-pin No. 1 of series Y positions the matrices B and B^1 of the first vertical column as indicated by the broken line y in Fig. 2. The gauge-pin No. 2 acts for the second vertical column of smaller matrices B and is not required for positioning any of the matrices B^1 ; gauge-pin No. 3 acts to position the matrices B and B^1 of the third column; gauge pin No. 4 acts to position the smaller matrices B in the fourth column, and is not required for any of the larger matrices B^1 . Gauge pins 5, 35 7, 9, 11 and 13 act to position the small and the large matrices B and B^1 in the fifth, seventh, ninth, eleventh and thirteenth columns respectively, as indicated by the broken lines y , and gauge pins 6, 8, 10 and 12 act to position the small matrices B in the corresponding vertical columns and are not required for the large matrices B^1 .

The centering cavities b of the small matrices B are arranged central of the body of the matrix in both directions while the centering cavities of the large matrices B^1 are central in one direction only. Conveniently the matrices are supported on rods C which are supported at their ends in openings a^1 50 in the frame of the die case and are held in position by a plate or bar A². These suspension rods pass through central holes b^1 in the body of the matrices. The matrices may, however, be supported upon bars and fingers such as described in the specifications of U. S. Letters Patent 784,245 and 980,959.

The particular matrix from which a cast 60 will be made will be the one which stands at the intersection of a vertical column positioned by a particular gauge-pin of series Y and a horizontal row positioned by a gauge-pin of the series X and when so positioned the centering cavity in the matrix will be directly under the matrix centering and clamping pin of the casting machine.

For example, if the matrix B¹¹ representing the character E is to be cast from, then the pin 9 of series X and the pin 7 of the series Y will be actuated.

Although only eight of the available fifteen unit values or horizontal rows are required in the above arrangement for positioning matrices, there being matrices only of eight different unit values, yet according to the present invention the die case can respond to anyone of the remaining seven gauge-pins so that a wider range for the justification of a line is provided for than in hitherto known schemes for casting and composing single type from "abnormal" 75 matrices on a "standard" machine since the mechanism and gauges for positioning the die case in one direction of its movement also moves the justification devices as hitherto. When one of the gauge-pins in series X 80 is projected to effect the setting of the justification mechanism or wedges, the positioning mechanism will move the die-case but as the pump is rendered inoperative no cast 85 will take place and the cone-pin for clamping the matrix on to the mould will descend, and if there is no matrix cavity underneath, the pin will be arrested by the die protecting plate A¹. Thus the full range of justification positions is available and can be 90 dictated and used without damage to any part of the machine. In hitherto known schemes, as already stated, only the positions corresponding to actual matrix 95 positions could be used for justification. 100

In the arrangement illustrated in Figs. 3 and 4 a still wider range of unit values of matrices is provided than in the arrangement above described. In this second arrangement each of the fifteen gauge-pins for 105 positioning the die case in the direction according to the unit value of the matrices is employed to represent a row, or one or more matrices of, a different unit value, thus permitting of a larger number of different unit 110 values being included or permitting more than one row of matrices of the same unit value being placed in the die case.

In this arrangement a row of matrices does not run from side to side of the die 115 case, there being four matrices B of the smaller size omitted from the first four horizontal rows and two matrices B^1 of the larger size omitted from the remaining four horizontal rows. In the central position of 120 the die case are placed matrices B and B^1 which form short rows or groups, the short rows being placed intermediate of the main rows so that the upper and lower edges of the faces of the matrices coincide with the 125 centre line of the matrices of the main rows.

In the embodiment illustrated there are four horizontal rows each containing four matrices B of the smaller size and three horizontal rows each containing two mat- 130

rices B^1 of the larger size employed. The first main horizontal row of matrices is positioned by gauge pin No. 1 of the series X, the first short row is positioned by the gauge pin No. 2; the second, third, fourth, fifth, sixth, seventh and eighth main rows are positioned by the gauge pins Nos. 3, 5, 7, 9, 11, 13 and 15 respectively; and the second, third, fourth, fifth, sixth and seventh, short rows are positioned by gauge pins 4, 6, 8, 10, 12 and 14 respectively.

Between the matrices of the short rows and the sides of the die case are spaces which are filled up by blanks or blocks b^2 . The pins of series X operate in this example in the same manner as with the previous example. The matrices are suspended on rods or bars C (see Fig. 6), which pass across the die case and are supported by their ends in openings in the opposite sides of the frame of the die-case. These rods do not pass through central openings in all the matrices, they pass through central openings in the matrices of the main rows, and rest in external side grooves b^2 in the matrices of the short rows as shown in Figs. 5 and 7 of the drawings.

We claim:

1. A matrix case comprising a frame capable of holding a definite number of setwise rows of normal matrices and adapted to be used in a type casting and composing machine provided with matrix case positioning mechanism capable of said definite number of positions in a pointwise direction, each position representing a definite setwise dimension for the type to be produced, rows of matrices in said case of a size to embrace in a pointwise direction two of said definite positions, and a positioning cone hole on one end of each matrix and central thereof in a pointwise direction to cause the central positioning of each matrix row with reference to one of the said definite positions whereby the setwise matrix rows are less in

number than the said positions and those positions corresponding to matrix rows are central of said rows in a pointwise direction.

2. A die case and matrices therein, all matrices being of the same pointwise size, and certain matrices being arranged in horizontal or setwise parallel rows, with other matrices staggered or set-off relatively to these rows, the amount of set-off being less than the pointwise size of the matrices.

3. In a die case, the combination with matrices arranged in setwise rows and matrices staggered or set-off relatively to these rows, the amount of set-off being less than the pointwise size of the matrices and all of the matrices being of the same pointwise size, of suspension bars passing through central openings in certain matrices and resting in external side grooves in other matrices.

4. A matrix case comprising a frame capable of holding a definite number of setwise rows of normal matrices and adapted to be used in a type casting and composing machine provided with matrix case positioning mechanism capable of said definite number of positions in a pointwise direction, each position representing a definite setwise dimension for the type to be produced, rows of matrices in said case of a size to embrace in a pointwise direction two of said definite positions, and a positioning cone hole on one end of each matrix and central thereof in a pointwise direction to cause the central positioning of each matrix row with reference to one of the definite positions, certain of the matrices of a row being staggered or offset one centering position in amount, so as to embrace a different one of said positions from that of the other matrices of the row, whereby two setwise dimensions of types may be produced from a single staggered row.
